STEAM HEATING

Ellis Burrell, Chicago, Ill., assignor to Evenaire
Regulator Company, Chicago, Ill., a corpora-
tion of Illinois

Application June 9, 1932, Serial No. 616,280

3 Claims. (Cl. 237—10)

This invention relates to steam heating systems and more particularly to an arrangement of control devices therefor, whereby these devices are successively in action to bring about, at pre-determined intervals, a pressure condition within the system, with air trapped in the radiators and released therefrom according to the heat delivery requirement at the different radiators. The pressure condition is followed by a fall in 10 pressure to less than atmospheric pressure and by replenishing the air in the system, before a successive rise in steam pressure. In this manner the heating system may be controlled and cause the delivery of heat from various radiators to 15 correspond with the heating requirements at different locations in the building, in accordance with changes in outside temperature conditions and heat losses from the building.

It is an object of the invention to provide in a 20 gravity circulating steam heating system means for causing a drop in pressure therein at regular intervals, to below atmospheric pressure, and admit air to the system for the purpose of permitting control of heat delivery from the system. It is also an object of the invention to provide 25 for steam pressure at regular intervals alternately with an air intaking condition of the system. A further purpose of the invention is to provide a steam heating system which will permit of dispensing with equipment such as the 30 customary radiator control valves and air inlet means at the radiators which are for the purpose of permitting condensate to drain back to the boiler in one-pipe systems. A further purpose 35 of the invention is to provide an improved air inlet means remote from the radiators, and an improved device for releasing air at the radiators according to the extent it is desired to have the radiators filled with steam.

40 These objects are accomplished by heating systems as illustrated in the accompanying drawings, in which:—

Figure 1 diagrammatically illustrates the invention as applied to an intermittently hand fired 45 boiler in a steam heating system, which may be operated so that the steam supplied to the radiators and the return of the condensate from the radiators is through one conduit, or separate conduits may be used for the supply and return.

50 In either case, the circulation is by gravity.

Fig. 2 shows a system similar to that illustrated by Fig. 1, except as modified to bring about intermittent supply of steam, although the boiler is kept at steady pressure.

55 Fig. 3 is a diagram showing the system as ar-

ranged in connection with a boiler which is heated by an intermittently operated oil burner.

Fig. 4 diagrammatically illustrates the system in connection with an automatically stoked boiler.

Fig. 5 is an enlarged sectional detail showing 60 the air inlet valve.

Fig. 6 is an end view of the valve shown in Fig. 5.

Fig. 7 is an enlarged front view, with the cover 65 omitted, of the thermostatic device for releasing air from the radiators according to a lowering of room temperature.

Fig. 8 is a side view of the regulator shown by Fig. 7.

Fig. 9 is a sectional detail taken on the line 70 9—9 of Fig. 8, to show the arrangement of a check valve for preventing air from entering the radiator through the air outlet port of the regulator.

The improvements herein described relate to 75 the use of air in steam heating systems in which the condensate water is generally returned to the boiler by gravity, and which are often referred to as one-pipe systems, although a separate return pipe may be provided for without changing the character of the system in so far as the present improvements are applicable thereto. In such a system of steam heating, the steam is supplied 80 at a pressure above that of atmosphere, and the water condensing in the radiators returns to the 85 boiler by gravity.

In order to insure proper draining of the radiator, it is generally necessary to leave the steam 90 inlet valve of the radiator open. The radiator inlet valves are not necessary in the arrangement herein disclosed, and the quantity of steam entering a radiator is not regulated by the steam valve, but is regulated by the release of air from the radiator, thus making room for the entering 95 steam.

In the present system, regulation of the heat 100 delivery of different radiators is effected by releasing more or less air from such radiators, and replenishing the air so released. The system is allowed to cool at intervals and take in more air. The air relief valves at the radiators depend for 105 operation upon room temperature changes. The boiler pressure may be maintained constant, or is raised and lowered at definite intervals, but the feed of steam to the system is controlled by the operation of a timing mechanism which insures shutting off the steam supply at intervals and allowing the pressure to drop below atmospheric pressure, at which time air is supplied to the system, and then upon a rise in pressure the 110

air is released at the various radiators, or pocketed therein, depending upon room temperature conditions.

The drawings illustrate various means for interrupting the steam supply. Provision is also made for changing the operation of the system when the fires are banked for the night, so that it may continue to supply steam to the radiators at less than atmospheric pressure.

10 Referring to the arrangement illustrated by Figure 1, the boiler 1 is shown provided with a customary check damper 2, draft damper 3 and firing door damper 4 under the control of a lever 5. This lever is shifted to control the setting of the dampers to increase or decrease the rate of combustion by a pressure regulator 6, or an electrically heated expansion motor 7, which is in a circuit 8, under the control of a clock actuated switch 9.

20 Cable connections 10 and 10' are made between the lever 5 and the dampers 2, 3 and 4. When the lever is shifted in one direction, the dampers are adjusted to decrease the normal rate of combustion and permit the steam pressure to drop to zero. This occurs at intervals several times a day, and when the radiators, which are indicated at 11, cool sufficiently to cause a partial vacuum in the system, an air inlet valve 12 in the steam supply main 13 opens and allows the system to 30 fill with air above the water level therein.

When the switch 9 opens under the action of the clock, the rate of combustion in the boiler is increased as the dampers are restored to normal condition. As the steam pressure rises, the air in the supply main 13 is released by the customary air venting means 14, with which such supply lines are generally equipped, but the air pocketed in the radiators is either retained therein or released therefrom by means of individual relief 35 valves or regulators 15, depending upon room temperatures where these radiators are located. This regulator is illustrated by Figures 7, 8 and 9. The outlet port 16 of the regulator is formed to provide a seat for a valve 17 at the end of the 40 thermostatic element 18, which is subject to the temperature of air passing upwardly at the end of the radiator. The regulator is insulated from the radiator by a spacing element 19 of bakelite, which carries a nipple by which the 45 regulator is attached to the radiator.

The thermostatic strip is fulcrumed on a knife-edge pin 21, carried by a post 22. The thermostatic element is held against its fulcrum by a spring 23, and its angular setting for operation at 50 some predetermined temperature is made by eccentric 24, which may be rotated by setting lever 25. The eccentric bears against a screw 26 passing through the lower end of the thermostatic element.

60 The outlet port 16 communicates with a chamber 27 formed in the body 28 of the regulator. The chamber 27 communicates with a hollow portion 29 of the regulator body 28 by passageways 30 and 31. Thus, if the thermostatic valve 17 is off of its seat, air in the radiator may escape through the hollow nipple 20 into the hollow body portion of the regulator, and through outlet port 16, but air cannot enter the radiator through the regulator, as the latter is provided with a check 65 valve 32, which may be a glass disc in the chamber 27.

If the pressure within the radiator is less than atmospheric pressure, the disc 32 will seat over the passageway 30, but is lifted from its seat when 75 the air pressure within the radiator exceeds the

atmospheric pressure on the opposite side of the disc. The hollow part 29 of the regulator body 28 carries oiled metallic wool for filtering the air passing through the regulator, and thus stops impurities from lodging upon the valve seats.

Figure 2 illustrates the control system as modified for application to gravity steam heating systems where the steam is supplied at some constant pressure. In such case, in order to operate the system to bring about alternate pressure and vacuum conditions, it is necessary to shut off and open up the steam supply line at intervals. This is done by means of an electrically operated shut-off valve 33, the circuit of which is controlled by a clock or manually operated switch 34. Otherwise, the operation of the arrangement shown by Fig. 2 is the same as that shown by Fig. 1, the regulators 15 releasing air from the radiators to the extent that heat is required at the location of the radiators, and during the interval that steam pressure is maintained.

When the steam supply line is shut off and the radiators cooled to a partial vacuum condition, the system is recharged with air through the automatic inlet valve 12. The air vent 14 in the radiator supply conduit 35 is of the usual thermostatic type which opens on air pressure but closes when subjected to the heat of the system, or vacuum. The arrangement shown by Fig. 2 is applicable in zoning systems, where a constant supply of steam 105 is available for different zones.

Figure 3 is another variation illustrating the time-actuated means 36 for bringing about alternate pressure and vacuum conditions.

Figure 4 also shows a modified means for 110 bringing about the desired repeated cycles of operation whereby alternate pressure and vacuum conditions occur in the system when the boiler is fired by an automatic stoker. The stoker is indicated diagrammatically at 37. It 115 is driven by an electric motor in a circuit 38 controlled by a clock-actuated switch 39.

The furnace damper 40 is adjusted by a heat motor 41, the coil of which is in a circuit 42 also under the control of the clock-actuated switch 120 39. Otherwise the system operates the same as those previously described, the air intake being through a valve 12 and the release of air from the radiators by the regulators 15 when the room temperature drops below the point at which the 125 regulators are set.

The air inlet valve, illustrated by Figures 5 and 6, is normally closed when pressure conditions exist in the system, as the valve disc 45 is then forced against its seat 46. The disc 45 is 130 preferably glass to provide a hard non-wearing and non-corroding surface for engaging the seat.

The valve disc 45 is supported by a bent arm 49 pivoted to the body of the valve on pin 50. The spring 47 bears between the disc 45 and a 135 shoulder 51 on arm 49 and the disc can move relatively to the arm but this arm is counterweighted at 52 to resiliently support the disc.

The screw head 53 on the end of arm 49 serves to hold the spring 47 under compression.

140 When the difference in pressure on opposite sides of the disc causes the valve to open or close, the arm 49 rocks on its fulcrum 50, and the angular setting of the disc, with reference to the seat, changes but upon the seating action the 145 spring allows the disc to adjust itself to the seat. At night time when the steam pressure may be kept low throughout the night, and it is desired to prevent the opening of valve 45, it may be locked to its seat by eccentric 54 operated by 150

lever 55. The arm 49 is cut out at 56 so as to be clear of the eccentric in one position of lever 55. When the disc is locked to its seat, the heating system may be operated as a vapor system, no air being admitted thereto and the radiators are filled with the low pressure steam.

In the operation of any of the arrangements illustrated by the diagrams, when the fires are checked or the steam is cut off after definite time intervals, the condensing steam in the radiators causes the pressure in the system to fall below atmospheric pressure at which time the automatic air intake valve opens and floods the system with air. Then when the clock-control switch, indicated at 9 Figure 1, at 36 Figure 3, and at 39 Figure 4, closes thus causing steam pressure to be built up in the system, the air in the main steam heat lines is vented by the air vents 14 until these devices are heated by steam temperature when they close. The remaining air, which is pocketed in the radiators and the conduits leading thereto, is slowly vented through the regulators 15 until the rooms in which the radiators are located reach the temperature at which the regulators are set for closing. In this manner the radiators are controlled to maintain a rate of heat delivery which is not in excess of that required for maintaining a desired room temperature.

In some heating systems of this general class it has been the custom to admit air thereto at each radiator, having the effect of quickly cooling the radiator. In the present arrangement a single air inlet valve is employed for a group of radiators and it is located at or near the boiler. The air is warmed in its passage through the conduits leading to the radiators and it is thus possible to conserve the heat in the radiators, and the arrangement also makes it possible to have a central control convenient for either manual or automatic operation.

The arrangement has the further advantage in that by admitting air to the system only at a central point there is only one device requiring adjustment for preventing any air from entering the system for example at night when the pressure is low and it is desired to cause the continuous circulation of steam or vapor.

In large buildings where the system is divided into a plurality of independent zones at least one air inlet valve is required for each zone.

When the fires are banked for the night, it is desirable in many cases to supply heat at a low temperature to all radiators and to prevent air from entering the system. By having a single air inlet valve 12 for the system and located near the boiler, a convenient means is afforded for preventing ingress of air and for this reason the valve 12, Figure 5, is provided with the shut-off lock element 55. The fire door damper 4, Figure 1, is unhooked so that it may remain closed during the night and thus conserve heat by preventing a draft over the fire. The clock operated switch controlling the heat motor circuit remains closed. These devices, being stand-

ard articles, are known as program clocks, the switch opening means being effective only during the day.

I claim:

1. In a system of temperature control for steam heating systems of the gravity return type, a steam heating system comprising a source of steam supply, a plurality of radiators and conduit connections between said source of supply and radiators, each of said radiators being equipped with an air release valve and means which prevents the entrance of air into the radiators through said valve, thermostatic means for controlling the operation of said valves, to open the valves upon lowering of temperatures to predetermined points, an air inlet valve mounted on the conduit connections between the source of steam supply and the radiators, said air inlet valve being constructed to open by atmospheric pressure and admit air to the system only when the pressure therein drops below that of the atmosphere, and means for periodically reducing the steam pressure in the heating system below atmospheric pressure.

2. In a system of temperature control for a steam heating system of the gravity return type, a steam heating system comprising a source of steam supply, a plurality of radiators and conduit connections between said source of supply and radiators, each of said radiators being equipped with an air release valve and a check which prevents the entrance of air into the radiators through said valve, thermostatic means for controlling the operation of said valves, to open the valves upon lowering of temperatures to predetermined points, an air inlet valve mounted on the conduit connections between the source of steam supply and the radiators constructed to automatically admit air to the system when the pressure therein drops below atmospheric pressure, means for periodically reducing the steam pressure in the heating system below atmospheric pressure, and means for preventing the opening of said air intake valve.

3. In a system of temperature control a steam heating system of the gravity return type, a steam heating system comprising a source of steam supply, a plurality of radiators and conduit connections between said source of supply and radiators, each of said radiators being equipped with an air release valve, thermostatic means for controlling the operation of said valves to open the valves upon the lowering of the temperatures to predetermined points, said air release valves being equipped with checks for preventing inflow of air therethrough when the pressure within the radiators is less than atmospheric pressure, an air inlet valve mounted on the conduit connections between the source of steam supply and the radiators constructed to automatically admit air to the system when the pressure therein drops below atmospheric pressure, and means for periodically reducing the steam pressure in the heating system below atmospheric pressure.

ELLIS BURRELL.
